UNITED STATES PATENT OFFICE.

DAVID S. JOHNSTON, OF KNOXVILLE, TENNESSEE.

FIRE-HOSE NOZZLE.

1,072,951.

Specification of Letters Patent.

Patented Sept. 9, 1913.

Application filed October 14, 1911. Serial No. 654,666.

To all whom it may concern:

Be it known that I, DAVID S. JOHNSTON, a citizen of the United States, residing at Knoxville, in the county of Knox and State of Tennessee, have invented a new and useful Fire-Hose Nozzle, of which the following is a specification.

This invention has reference to improvements in hose nozzles and particularly fire 10 hose nozzles, and its object is to provide a nozzle whereby the operator may be completely protected from the effects of fire and smoke by a wall of water delivered by the nozzle in a manner to interpose between 15 the source of fire or smoke or both and the operator.

In accordance with the present invention the nozzle is provided with means for producing a gill spray at an intermediate point 20 of the nozzle whereby when a full stream is issuing from the mouth of the nozzle the operator is enveloped in spray in the form of a sheet of ample diameter permitting the operator to approach close to the flame, 25 while at the same time being fully protected from the effects of heat and smoke, and provision is made for varying the direction of this sheet or screen of spray to protect the operator on either side if necessary, while 30 not materially affecting the stream of water issuing from the mouth of the nozzle.

The nozzle also includes means for regulating the outlet for various purposes, as for 35 producing either a round stream of water of great carrying power, or a flattened stream of great spreading power, or intermediate conditions enabling the operator to regulate the nozzle for varying conditions met in fire fighting.

40 The invention will be best understood from a consideration of the following detailed description, taken in connection with the accompanying drawings forming a part of this specification, with the understanding, however, that while the drawings show a practical form of the invention it is susceptible of other embodiments while still retaining the salient features of the invention, and, therefore, the invention is not confined 45 to any exact conformity with the showing of the drawings.

In the drawings:—Figure 1 is a perspective view of the nozzle. Fig. 2 is a longitudinal diametrical section of the structure

shown in Fig. 1. Fig. 3 is a section on the 55 line 3—3 of Fig. 2 but drawn to a larger scale. Fig. 4 is a section on the line 4—4 of Fig. 2 but drawn to a larger scale. Fig. 5 is a section on the line 5—5 of Fig. 2 drawn to a larger scale. Fig. 6 is a side elevation 60 with some parts in section of the outlet end of the nozzle with the exit flattened. Fig. 7 is an end elevation of the exit end of the structure shown in Fig. 1. Fig. 8 is a section on the line 8—8 of Fig. 6. Fig. 9 is a 65 perspective view of the exit end of the nozzle showing a somewhat different means for regulating the form of the stream issuing therefrom from that shown in Fig. 1 and associated views. 70

In the drawings, there is shown a nozzle structure comprising two members 1 and 2, respectively, the member 1 having at one end a threaded socket or bell 3 for attachment to hose, and at the other end the member 1 75 is provided with a collar 4 constituting in effect a radial flange. At an intermediate point the member 1 has applied thereto a sleeve 5 which may be formed at one end with an outstanding flange 6 and applied 80 to the exterior of the sleeve 5 is a ring 7 held in place by an appropriate number of screws 8 or by any other suitable means. The sleeve 5 is held to the member 1 by a set screw 9 or as many set screws as may be found ad- 85 visable, or any other means for securing this sleeve fixedly to the member 1 may be employed. Surrounding the sleeve 5 and carried thereby between the flange 6 and ring 7 is a ring 10 having on its inner face a cir- 90 95 100 105 ular series of gear teeth 11, so that the ring 10 with the teeth 11 constitute a circular gear with the teeth interior thereto. This circular gear is provided at one point with an outstanding handle 12 which may be sub- stantially radial to the gear. The sleeve 5 is cut away at appropriate points, as indicated at 13, for the reception of pinions 14, the sleeve being shown as provided with three such cut away portions equi-distantly disposed, that is, separated at angles of one hundred and twenty degrees. Each pinion is fast to one end of a shaft 15 to which reference will presently be made, the shaft at the end remote from the pinion being screw threaded for a distance as indicated at 16 in Fig. 2, and between the pinion and threaded portion provided with an external abut-

ment 17 engaging the collar 4 through which the shaft is extended, the threaded portion 16 being on the side of the collar 4 remote from the sleeve 5. Mounted on the member 1 between the sleeve 5 and the collar 4 is an annular slide 18 formed with a semi-globular extension 19 directed toward the flange 4 and in spaced relation to the portion of the member 1 surrounded by the said extension 19. The free edge of the semi-globular extension 19 may be brought to an approximately sharp edge 20, the sharpened edge being outermost.

The member 1 of the nozzle is in the particular construction shown substantially cylindrical throughout and the member 2 of the nozzle has a portion 21 approximately cylindrical, and from this cylindrical portion to the exit end the member 2 may be tapered as is customary in hose nozzles. On the cylindrical portion 21 of the nozzle member 2 there is mounted a sleeve 22 having an approximately semi-globular extension 23 similar to the extension 19 of the slide 18, and this extension 23 has its free end brought to an approximately sharp edge, as indicated at 24, the term sharp edge not necessarily meaning a cutting edge, but that the edge is beveled back so that the peripheral portion 30 presents but little surface.

The sleeve 22 is not made fast to the nozzle section 2, but is free to slide thereon, although the fit should be comparatively snug to prevent leakage. The two semi-globular members 19 and 23 have their sharpened edges presented one toward the other and the slide 18 and sleeve 22 are connected together in spaced relation by a suitable number of rods 25 joining the two members for simultaneous movement longitudinally of the nozzle as a whole. That end of the nozzle section 2 presented toward the nozzle section 1 is provided with a collar 26 similar to the collar 4 and serving as an annular flange, and the outer edges of these two flange members may be beveled to present comparatively sharp peripheral portions 27 adjacent one to the other, the facing portions of the two flanges being in substantially parallel relation one to the other. The flanges 4 and 26 have appropriate matching perforations 28 for the rods 25, so that there may be relative movements between the flanges and rods. The shafts 15 pass freely through appropriate passages in the slide 18 and through appropriate passages in the flange 4 and the threaded ends 16 of these shafts extend through threaded passages in the flange 26. By turning the internal gear 10 axially rotative movement is imparted to the pinions 14 and by the latter to the shafts 15 and through the screw threaded ends 16 of these shafts operate on the flanges 26 to cause the section 2 to move toward and from the section 1, whereby the space between the

flanges 4 and 26 may be made lesser or greater in accordance with the direction of movement of the shafts. The space between the two flanges is practically free, being impeded only by the presence of the shafts 15 and rods 25 and since these may be of comparatively small diameter the space between the flanges is for all practical purposes quite free.

Mounted on the section 1 is a segment 29 having notches 30 and mounted on the member 1 by means of a pivot 31 and appropriate ears 32 is a thumb lever 33 provided with a dog 34 adapted to the notches 30. This lever is connected by a link 35 to the slide 18, so that by an appropriate manipulation of the lever 33 the slide 18 and with it the sleeve 22 may be moved longitudinally of the nozzle irrespective of the adjustment of the two members of the nozzle one relative to the other. Because of the general globular shape of the associated slide 18 with its flange 19 and sleeve 22 with its flange 23 it may be termed a globe shift. In order to maintain the globe shift in fixed relation to the nozzle except for longitudinal movement thereon, splines 36 are provided about the member 1 and the inner surface of the slide 18 is appropriately cut away for the reception of these splines which prevent turning motion of the globe shift on the nozzle but permit longitudinal movement thereof on the nozzle.

Let it be assumed that the nozzle is appropriately attached to a fire hose and that water is flowing through it in the usual manner, or in a manner to be hereinafter described, and let it be assumed that the gear 10 has been manipulated to separate the flanges 4 and 26 to leave an appropriate space between them, and let it also be assumed that the globe shift is in an intermediate position such as shown in Fig. 2. Under these conditions there is issuing from the nozzle a stream of water depending upon the size of the nozzle and the pressure impelling the water. There is also issuing in a direction substantially radial to the longitudinal axis of the nozzle a wall of spray extending in all directions from the nozzle for a distance depending upon the pressure exerted on the water. In the drawings the passage between the two flanges at the meeting ends of the nozzle members is shown exaggerated as compared with the outlet of the nozzle, for in practice the wall of spray is not proportionally so massive as would be indicated from the drawings, for the wall of the spray does not interfere to any harmful extent with the water issuing from the mouth of the nozzle toward the fire, but this wall of spray is sufficient to act as an effective shield or screen for the operator, who, of course, is assumed to be a fireman. The wall of spray issuing laterally from the nozzle may be termed a gill spray and under

the position of the parts assumed this spray is in practice found amply sufficient to enable a fireman to approach within a very short distance of the flame with protection against both the heat of the flame and the smoke, a spray being found to be most efficient in dispelling smoke. The gill spray enables a fireman to approach more closely to a flame than would otherwise be the case and may rescue helpless persons and carry them away from the fire while under the protection and cooling effects of the wall or screen of spray. Moreover, the gill spray enables the fireman to approach very close to the source of fire and by such close observation without any great danger or inconvenience direct the stream of water where most efficient.

By moving the globe shift longitudinally of the nozzle structure so as to bring one semi-globular flange or the other into the path of the outflowing gill stream, the curved inner wall of the flange 19 or 23, as the case may be, will divert the gill stream so that it is thrown forwardly or rearwardly to thereby further protect the fireman from the effects of the flame. In actual practice it has been found that with a full stream playing through the nozzle a quarter inch opening for the gill stream will form a screen, curtain or wall of spray fifteen or more feet in diameter, warding off all heat and smoke and making it possible to approach within even less than one foot of the flame with a clear view ahead and full protection to the fireman on all sides and also above, especially when the lever 34 is in the rearmost notch 30 and a gill spray is directed rearwardly. In order that the effect of the gill spray upon the water pressure may be understood it may be stated that a quarter inch spray on a full size nozzle reduces the full pressure ahead by approximately ten pounds to the hundred.

By moving the lever 33 to the intermediate position and varying the gill spray from one quarter to one half inch in thickness as desired, a sheet of water or spray perpendicular to the longitudinal axis of the nozzle of fifteen or more feet in diameter is obtained, which sheet wards off the flames from right or left and makes a complete transparent curtain in front of the fireman. When the lever 33 is forward with the gill spray anywhere from one quarter to one half inch in thickness, the sheet of spray is directed forwardly, which with the full stream playing straight ahead retards flames from both sides, thus enabling a fireman to back out of a burning building in case of falling timbers or other like dangers, while at the same time being fully protected by the gill stream. The fireman has close at hand the handle 12 and lever 34 whereby the thickness of the gill stream and the relation

thereof to the longitudinal axis of the nozzle may be readily adjusted from time to time as occasion may demand, or where the gill stream is unnecessary the parts may be brought close together, so that the flanges 4 and 26 are in contact and the gill stream is thereby obliterated, the nozzle then acting as an ordinary nozzle so far as the adjustment between the two sections is concerned.

In fires conditions often arise where the solid circular stream is not as effective as a stream of other form. To provide for such contingency the small end of the section 2 has applied thereto a flexible cylindrical nose 37 which may be made of flexible wired rubber hose held to the end of the nozzle by a clamp ring 38 or otherwise. Pivoted to opposite sides of the nozzle section 2 near the exit end are levers 39 of the first order and corresponding levers on opposite sides of the nozzle are connected together by cross bars 40 at the outer ends and these cross bars may carry shoes 41 in engagement with the flexible hose extension 37. The ends of the levers 39 remote from the cross bars 40 are connected together on the same side of the nozzle by links 42 and these links are joined together and to another link 43 which in turn is connected to the corresponding yoke end 44 of a lever 45, the yoke end of the lever being in straddling relation to the nozzle section 2 and connected thereto by pivots 46. The lever is provided with a thumb latch 47 in operative relation to a rack 48 mounted on a casing 49 in turn carried by the end of the nozzle section and terminating in the nose 37, the casing 49 surrounding and protecting the lever and link system and is provided with a slot 50 for the passage of the lever. When the lever 45 is moved in one direction the shoes 41 are separated one from the other, so that the nozzle extension 37 expands to its full circular position. When the lever 45 is moved in the other direction the levers 39 are rocked on their pivots to bring the shoes 41 closer together thus flattening the flexible extension 37 thereby contracting it in one direction and elongating it in another. This causes the issuing stream to assume a more or less fan-like shape, whereby a broad stream of comparatively little thickness is projected although the relation between the width and thickness of the stream will depend upon the adjustments of the lever 45. In place of the flattening shoes, flattening blades 51 shown in Fig. 9 may be employed, these blades being carried by the corresponding ends of the levers 39 and extending beyond the outer end of the flexible nose 37. The flatteners 51 may be operated in a manner similar to the flatteners 41. The structure shown in Fig. 9 is particularly useful in connection with water towers where the fire may be fought from above and this

flattener will deliver a sheet of water from one-sixteenth of an inch upward which with full pressure will cover an area up to fifty feet in diameter or practically covering the 5 complete top of a building, the gill stream of course being under such circumstances closed. It will be understood, of course, that where heavy pressures are used suitable reinforcing is employed to resist such pressures, so that the parts will not become bent 10 out of shape.

The levers for manipulating the various parts may be arranged to lie close to the nozzle, so as to be out of the way when not 15 in use. The gill spray in a standard size nozzle has usually an adjustment from about one-half inch as maximum thickness to one-thirty-second inch, in use, or may be entirely cut off, and the parts are so arranged 20 that the entire movement of the circular gear need not exceed one turn for such purpose. The whole nozzle may be made of standard size to fit in the nozzle holders of fire fighting apparatus, such as are in common 25 use.

The flattening device for widening and thinning the stream issuing from the nose of the nozzle is particularly useful in the case of lumber or mill fires where there are stacks 30 of lumber, logs, etc., and a flat spray or stream will enter between the openings and reach a fire where a round stream loses the greater part of its efficiency by the splash 35 caused by coming in contact with the sides or ends of the piled lumber. Moreover, a round stream will often upset piles of lumber not only interfering with reaching the seat of the fire, but often endangering firemen, while with the flat stream the liability 40 of upsetting the piles of lumber is greatly reduced.

It is to be observed that the interior of the nozzle as a whole is of substantially constant diameter from the point of connection 45 with the nozzle holder to a point beyond the gill spray in a direction toward the nose of the nozzle and that the nozzle then tapers to the delivery end, so that there are no obstructions whatsoever within the nozzle 50 either in the form of adjusting mechanisms or shoulders, or other impeding devices to the outflow of the water. The pressure necessary to cause the projection of the gill stream laterally to the longitudinal axis of 55 the nozzle is due wholly to the tapering end of the nozzle, whereby there is superior pressure at the point of generation of the gill stream without any impediment to the flow of the stream at this point when the gill 60 stream opening is fully closed.

It is to be observed that the lever 45 is moved toward the discharge end of the nozzle to close such end so that when the nozzle is being dragged over the ground, as often 65 occurs, the lever will not catch on some ob-

struction and thereby cause the opening of the nozzle.

What is claimed is:—

1. A fire hose nozzle having a break in its continuity at an intermediate point, the 70 parts being adjustable one relative to the other in the direction of the longitudinal axis to increase or decrease the space between the adjacent ends, or to bring them into contact at will, and a directing member formed of two portions spaced apart and located on opposite sides of the break in the continuity of the nozzle and movable bodily lengthwise of the nozzle to direct a 75 gill stream issuing through the break in the 80 nozzle toward one end or the other of said nozzle.

2. A fire hose nozzle having a break in its continuity at an intermediate point with radially disposed walls, the parts being adjustable one relative to the other in the direction of the longitudinal axis of the nozzle to increase or decrease the space between the radial walls or to bring them into contact at will, and a directing member on the 85 nozzle exterior to the portion where the break occurs and including two portions spaced apart and movable together longitudinally of the nozzle to direct a gill stream 90 issuing through the break toward one end or 95 the other of the nozzle, at will.

3. A fire hose nozzle having a portion of substantially constant internal diameter and another portion tapering therefrom to the discharge end of the nozzle, the nozzle being separated into two members within the range of the portion of constant diameter, and means exterior to and accessible on the first named portion for the adjustment of the portion carrying the tapered part toward and from the other portion of the nozzle 100 in the direction of the longitudinal axis of the nozzle.

4. A fire hose nozzle having a break in its continuity at an intermediate point for 110 the production of a gill stream, and means for directing the gill stream toward either end of the nozzle at will comprising a two part interiorly expanded member surrounding the nozzle at the point of break in its 115 continuity and on opposite sides thereof, the two parts being in spaced relation one to the other and connected together for bodily movement in the direction of the longitudinal axis of the nozzle.

5. A fire hose nozzle comprising two aligned members, one member being movable toward and from the other member in the direction of the longitudinal axis of the nozzle, screw shafts carried by one member 120 and carrying and engaging the other member, pinions on the screw shafts at the ends thereof on the member carrying said shafts, a circular gear in engagement with the pinions and provided with manipulating means, 130

and a support for the gear on the carrying member of the nozzle for holding the gear in engagement with the pinions and permitting rotative movement of the gear.

5 6. A fire hose nozzle comprising two alined members, one member being movable toward and from the other member in the direction of the longitudinal axis of the nozzle, screw shafts carried by one member and carrying and engaging the other member, pinions on the screw shafts at the ends thereof on the member carrying said shafts, a circular gear in engagement with the pinions and provided with manipulating means, 10 and a support for the gear on the carrying member of the nozzle for holding the gear in engagement with the pinions and permitting rotative movement of the gear, the adjacent ends of the carrying and carried members of the nozzle being provided with exterior radial flanges in matching relation one to the other and movable one toward the other by the relative movements of the nozzle sections.

15 7. A fire hose nozzle comprising two alined members, one member being movable toward and from the other member in the direction of the longitudinal axis of the nozzle, screw shafts carried by one member and carrying and engaging the other member, pinions on the screw shafts at the ends thereof on the member carrying said shafts, a circular gear in engagement with the pinions and provided with manipulating means, 20 and a support for the gear on the carrying member of the nozzle for holding the gear in engagement with the pinions and permitting rotative movement of the gear, the adjacent ends of the carrying and carried members of the nozzle being provided with exterior radial flanges in matching relation one to the other and movable one toward the other by the relative movements of the nozzle sections, the screw 25 shafts extending through the radial flange of one nozzle section and having their threaded ends extending through and engaging the flange of the other nozzle section.

30 8. A fire hose nozzle comprising two alined sections movable relatively one to the other in the direction of the longitudinal axis of the nozzle for the production of a gill stream between the adjacent ends of the sections, and a globe-like structure in surrounding relation to the meeting ends of the nozzle sections and having parts in separated relation for the passage of the gill stream, said globe-like structure being 35 movable in the direction of the longitudinal axis of the nozzle for intersecting and directing the gill stream.

30 9. A fire hose nozzle comprising two alined sections movable relatively one to the other in the direction of the longitudi-

nal axis of the nozzle for the production of a gill stream between the adjacent ends of the sections, and a globe-like structure in surrounding relation to the meeting ends of the nozzle sections and having parts in separated relation for the passage of the gill stream, said globe-like structure being movable in the direction of the longitudinal axis of the nozzle for intersecting and directing the gill stream, one nozzle section 70 having means for adjusting it toward and from the other nozzle section, said means being accessible on the operator side of the gill stream opening and the globe-like structure having means for its adjustment 75 also located on the operator side of the gill stream opening.

10 10. A fire hose nozzle comprising two alined members movable relatively one to the other in the direction of the longitudinal axis of the nozzle, the meeting ends of the sections being provided with exterior radial flanges, a slidable member upon each section adjacent the flanged meeting ends and each terminating in a curved extension of semi-globe-like form exterior to the flanged ends of the sections, connecting means between the slidable members in turn extending through the flanged ends, an adjusting means for the globe like members on that section of the nozzle remote from the discharge end of the nozzle, screw shafts extending through the flange at the end of one section and having screw threaded ends 90 engaging the flange at the adjacent 95 end of the other section, and means for rotating the shafts comprising a circular gear and pinions mounted on the shafts and meshing with the gear, and a support for the circular gear and pinion ends of the 100 shafts carried by the member carrying the adjusting means for the globe-like structure.

11 11. A fire hose nozzle comprising two alined members movable relatively one to the other in the direction of the longitudinal axis of the nozzle, the meeting ends of the sections being provided with exterior radial flanges, a slidable member upon each section adjacent the flanged meeting ends and each terminating in a curved extension of semi-globe-like form exterior to the flanged ends of the sections, connecting means between the slidable members in turn extending through the flanged ends, an adjusting 110 means for the globe-like members on that section of the nozzle remote from the discharge end of the nozzle, screw-shafts extending through the flange at the end of one section and having screw threaded ends 115 engaging the flange at the adjacent end of the other section, and means for rotating the shafts comprising a circular gear and pinions mounted on the shafts and meshing with the gear, and a support for the 120 125 130

circular gear and pinion ends of the shafts carried by the section carrying the adjusting means for the globe-like structure, the peripheral edges of the flanges of the nozzle sections and the corresponding peripheral edges of the globe-like structure being beveled or sharpened where engaged by water.

In testimony, that I claim the foregoing as my own, I have hereto affixed my signature in the presence of two witnesses.

DAVID S. JOHNSTON.
